J. MARCH.

STEAM PUMP.

APPLICATION FILED MAR. 3, 1909.

962,906.

Patented June 28, 1910.

UNITED STATES PATENT OFFICE.

JOHN MARCH, OF DILLON, MONTANA.

STEAM-PUMP.

962,906.

Specification of Letters Patent. Patented June 28, 1910.

Application filed March 3, 1909. Serial No. 481,162.

To all whom it may concern:

Be it known that I, JOHN MARCH, a citizen of the United States, residing at Dillon, in the county of Beaverhead and State 5 of Montana, have invented certain new and useful Improvements in Steam-Pumps, of which the following is a specification.

My said invention consists in certain improvements in a compound steam pump; or 10 air compressor, whereby a very efficient construction is secured and one wherein economy of power and large capacity in operation are combined, all as will be hereinafter more fully described and claimed.

15 Referring to the accompanying drawings which are made a part hereof, and on which similar reference characters indicate similar parts, Figure 1 is a longitudinal horizontal section through a steam pump of my improved construction, Fig. 2 a longitudinal vertical action on the dotted line 2—2 in Fig. 1, and Fig. 3 a detail view on an enlarged scale.

In said drawings the portions marked A 25 represent the base or frame, B the engine cylinder and C, C' the pump or compressor cylinders. The base or main frame A is, or may be, of any appropriate construction suitable to support the other parts of the 30 machine and needs no special description.

The engine cylinder B is of uniform diameter and is provided with sliding heads 1 and 2, formed with steel packing rings in their peripheries, in the usual manner of 35 packing pistons. Head 1 is connected by connecting rods 3 with a sliding cross-head 4 the ends of which are mounted in slides or ways formed in the side pieces of the frame A. Sliding head 2 is connected by 40 connecting rods 5 with a cross-head 6 the ends of which are mounted to slide in ways in the frame A. Said cross-heads 4 and 6 are rigidly connected together by connecting rods 7. Said sliding cross-heads 4 and 45 5 connected by the rods 7 thus constitute a sliding frame. A piston 8 is mounted in said cylinder B between said heads and has a piston rod 9 extending from one side thereof out through the head 1 and is provided 50 with a cross-head 10 on its outer end. The sliding cross-head 4 is connected by toggle links 11 and 12 with said cross-head 10 on the outer end of said piston rod. The central pivot 13 of toggle 11 extends into a sliding block 14 mounted in a grooved way 15

extending across frame A. The central pivot 16 of toggle 12 extends into a similar block 17 mounted in the same groove on the opposite side of said way. A steam chest B' is mounted on one side of the steam cylinder B and a steam chest B² on its opposite side. Steam chest B' has a steam inlet pipe b connected with one side thereof and a steam exhaust pipe b' connected with its opposite side. Said steam chest is divided 65 into a steam inlet chamber and a steam exhaust chamber. A sliding valve 20 is mounted in a groove in said steam chest being formed with ports 21 and 22 adapted to register with ports 23 and 24 leading into 70 the engine cylinder. A similar, but spring-supported sliding valve 25 is mounted in the steam chest B² formed with ports 26 and 27 adapted to register with ports 28 and 29 in said cylinder. An operating rod 30 is connected with sliding valve 20 and an operating rod 31 with sliding valve 25. The outer ends of said rods extend through opposite ends of a cross-bar 32 mounted on sliding cross-head 4 and are provided with adjustable strikes 33, 34, 35 and 36 respectively with which said bar 32 is adapted to contact, as the sliding cross-head 4 approaches the limit of its movement, to shift said sliding valves 20 and 25 from the position shown 85 in Fig. 2 to the reverse position.

The cylinder C is of common construction having inlet ports on one side at each end controlled by valves 40 and 41 and connected by a branch pipe to a main inlet pipe c and on the opposite side provided with exhaust ports controlled by valves 42 and 43 connected by a branch to a main exhaust pipe c'. A piston 44 is mounted in said cylinder and connected by a piston rod 45 with the cross-head 10 on the end of the piston rod 9. Cylinder C' is of a similar construction having an inlet port on one side controlled by valves 46 and 47 connected by branch pipes to an inlet pipe c² and with exhaust ports 100 on the opposite side controlled by valves 48 and 49 and connected by a branch to an exhaust pipe c². A piston 50 is mounted in said cylinder connected by a piston rod 51 with the sliding cross-head 6. 105

The inner end of piston rod 9 connected to the piston 8 is formed enlarged or surrounded by a cylinder 55 of approximately one-half the diameter of the bore of cylinder B, said portion 55 being of a length to ex- 110

tend through the head 1 and occupy a sufficient portion of the area of the chamber between head 1 and piston 8 to divide the cylinder B into a high pressure and low pressure expansion chamber.

In operation the parts being in the position shown in Fig. 2 and the steam coming from the steam inlet pipe b through the steam chest B' and the ports 21 in sliding valve 20 and 25 in cylinder B, comes into the space between head 1 and piston 8 and expanding drives said piston and head in opposite directions, the piston 8 operating through the piston rod 9 to drive piston 44 in cylinder C from the position shown in Fig. 1 toward the opposite end of said cylinder, while the movement of head 1 through the connection with cross-head 4, connecting rods 7, cross-head 6, and piston rod 51 draws piston 50 in cylinder C' from the position shown in Fig. 1 toward the opposite end of its cylinder and at the same time slides head 2 toward the approaching piston 8 until said head 2 and piston 8 occupy substantially the same position relative to each other as to head 1 and piston 8 as shown in the drawings. When this position is approached the cross-bar 32 comes in contact with the strikes 34 and 36 on the outer ends of valve rods 30 and 31 and shifts the valves 20 and 25 to close ports 23 and 24 and open the ports 28 and 29 through the steam chest B' into the chamber between the head 2 and piston 8. Said chamber being of a larger area the steam from the chamber between piston 8 and head 1 passes into said chamber and expands driving the parts in the opposite direction, thus securing a double expansion of the steam. When the head 1 and piston 8 again approach each other the valves are again shifted and the live steam admitted into the high pressure chamber as before when the first expansion takes place in the high pressure chamber and the spent steam is exhausted from the low pressure chamber. As the piston 44 is driven in one direction it will suck in the air, or other fluid, through the inlet valve behind, in the direction of its motion, and drive out under pressure the fluid in front, in the direction of its motion, while the piston 50 in the opposite cylinder C' is operating in a like manner but in a reverse direction. The pipes c' and c'' are, of course, intended to lead to a single high pressure pipe but may be separately connected if preferred.

By this arrangement an engine and pump, or compressor, is provided wherein the expansive force of the steam is used in both directions and balances the strain and vibration while its entire force is directed upon

the work and no part of it is spent against the stationary immovable parts.

Having thus fully described my said invention, what I claim as new, and desire to secure by Letters Patent, is:

1. In a steam pump, the combination of a frame, a steam cylinder, sliding heads in the opposite ends of said cylinder, a sliding frame to which said heads are connected, a piston between said sliding heads, pumping cylinders adjacent to each end of said steam cylinder containing pistons, the piston of one being connected to the piston rod of the piston in the steam cylinder and the piston of the other connected to the sliding frame with which said sliding heads are connected, and the steam controlling mechanism, substantially as set forth.

2. In a steam pump, the combination of a frame, a steam cylinder, sliding heads therein, a sliding frame mounted in the main frame and connected to said sliding heads, a piston between said sliding heads, a piston rod extending out through one of said sliding heads with a cross-head on its outer end, toggle links connecting the sliding frame with said cross-head hinged to sliding blocks mounted in a transverse way, the pumping cylinder provided with controlling inlet and exhaust valves, pistons in said pumping cylinders one of which is connected to the piston rod of the steam cylinder piston and the other of which is connected to the sliding frame connected to the sliding heads on the steam cylinder, and the steam controlling mechanism, substantially as set forth.

3. In a steam pump, the combination of a frame, the steam cylinder, the pumping cylinders, the valves for controlling the inlet and exhaust ports of said pumping cylinders, the sliding heads in said steam cylinder connected to a sliding frame, said sliding frame, a piston between said sliding heads, a connection between said piston and the piston of one pumping cylinder, a connection between the sliding frame and the piston of the other pumping cylinder, steam inlet and exhaust ports leading into the steam cylinder on the opposite sides of the piston, sliding valves for controlling said ports, and a connection between the sliding frame and said sliding valves for shifting their position, substantially as set forth.

In witness whereof, I have hereunto set my hand and seal at Washington, D. C. this 26th day of February, A. D. nineteen hundred and nine.

JOHN MARCH. [L.S.]
